United States Patent Office

Des. 227,637
Patented July 10, 1973

227,637

BASE FOR ORGAN BENCH

Roy W. Rust, Independence, Ky., and Leslie J. Weigel,
Hubert S. Shearin, and Emerson Henthorn, Cincinnati,
Ohio, assignors to Manual Arts Furniture Company,
Cincinnati, Ohio

Filed Sept. 13, 1971, Ser. No. 180,248

Term of patent 14 years

Int. Cl. D6—02

U.S. Cl. D6—196

FIG. 1

FIG. 2

FIG. 3

FIG. 1

FIG. 2

FIG. 3

FIG. 4

FIG. 1 is a perspective view of a base for organ bench in accordance with the invention.

FIG. 2 is a top plan view thereof.

FIG. 3 is a vertical sectional view taken along the line 3-3 of FIG. 2.

FIG. 4 is a bottom plan view of the base.

FIG. 5 is an enlarged vertical sectional view taken along the line 5-5 of FIG. 4.

FIG. 6 is a front elevational view of the base.

FIG. 7 is a rear elevational view of the base.

FIG. 8 is an end elevational view of the base taken from either the right or left side of FIG. 6, the opposite end views of the base being the same.

We claim:

The ornamental design for a base for organ bench, as shown.
